STABILIZING MEANS FOR A ROTARY REAMER
Martin Hoerer, Highland Park, Ill., assignor to Super-Cut,
Inc., Chicago, Ill., a corporation of Illinois
Filed Sept. 10, 1962, Ser. No. 222,490
8 Claims. (Cl. 51—34)

The present invention relates generally to reaming apparatus and has particular reference to stabilizing means whereby a rotary abrasive type reaming tool, such as is employed for imparting tapered, frusto-conical or other shapes to the rim regions or edges of holes that have been previously drilled in ceramic or other brittle materials, is prevented from chattering due to eccentric wobbling thereof with the result that the material undergoing abrasion is less likely to be subject to chipping.

Occasions arise where it is desirable or necessary to provide in marble, granite, slate and similar brittle materials, holes which have slanting or tapered sides. An example of this is in connection with tables which are employed for playing pocket billiards and are commonly referred to as pool tables. The playing surfaces of professional and commercial pool tables of the better grade are invariably of felt-covered slate or marble and the holes which are provided at the corners and sides of such tables are provided with frusto-conical or sloping sides to the end that clearance for entry and dropping of the balls into the pockets will be established as soon as the balls encounter the rims of the holes. The pocket areas, therefore, need not project unduly inwardly of the table rails nor need the height of the rails be made unduly high. Heretofore, in the manufacture of a pool and similar game table having a relatively thick slate or marble slab for its playing surface, it has been the practice in the creation of tapered holes in the slab, first, to drill cylindrical holes through the slab by way of a conventional core drill and, thereafter, to taper the holes by chipping away the slate or marble material around the holes by way of a conventional hand tool, such as a chisel, gouge, reaming file or the like. These operations have required the use of highly skilled labor and, in addition, they have been time-consuming, thereby adding appreciably to the cost of producing the pool tables. Efforts to dispense with the use of such skilled labor by the use of suitably shaped abrasive reamers have not been satisfactory, even when diamond abrasive reamers have been employed, this being due to chattering of the reamers against the sides of the holes undergoing shaping and a consequent chipping of the material being worked upon, or even more serious, the creation of cracks in the slabs. Due to the proximity of the holes undergoing reaming to the edges of the slab, the use of such power-driven reamers results in breaking of the connecting webs along the outside edges of the holes.

The present invention is designed to overcome the abovenoted limitations that are attendant upon the reaming of holes in marble, slate, granite and similar materials, especially in slabs formed of such materials. Toward this end, the invention contemplates the provision of a novel stabilizing means whereby the rotary spindle and the abrasive-type reaming tool which is carried thereby are given reaction support against eccentric or other wobbling during advancement thereof toward the work, this stabilizing means assuming the form of a novel piloting arrangement whereby the actual reaming tool finds piloting support in the bed plate of the drill press or other machine which is employed for rotating the reaming tool.

A conventional pilot support for the forward end of an advancing reaming, honing or similar abrasive tool establishes reaction forces which are applied to the tool in the central or axial region thereof. Such a pilot sup-

2

port is satisfactory for the reaming of small diameter holes or bores but, where large holes are concerned, the application of piloting reaction force to the central region of the abrasive tool will not altogether eliminate chattering of the tool against the side of the hole undergoing abrasion. According to the present invention, a firmer piloting support than has heretofore been provided for the forward end of a rotary abrasive-type reaming tool is provided, such support utilizing a relatively massive anti-friction thrust bearing which is affixed to the bed plate of the drill press. The thrust bearing serves rotatably to support a reaction hub which is coaxial with the tool-carrying spindle and guide posts project upwardly from the outer marginal peripheral portion of the reaction hub and extend into guide bores which are provided in the peripheral region of the abrasive tool where radial reaction forces are applied to the tool and, consequently, to the spindle which drives the tool, these forces being effective in close proximity to the annular working abrasive area of the tool. By such an arrangement, any flexibility which may be inherent in either the spindle or in the body of the abrasive tool will not operate to allow lateral displacement of the abrasive working area or areas of the tool.

25 The provision of a stabilizing means for a rotary reamer such as has briefly been outlined above being among the principal objects of the invention, numerous other objects and advantages will become readily apparent as a consideration of the following detailed description.

In the accompanying single sheet of drawings forming a part of this specification, one illustrative embodiment of the invention has been shown.

In these drawings:

35 FIG. 1 is a fragmentary sectional view taken substantially centrally and vertically through a rotary abrasive-type reaming tool and showing the tool in operative position before descending upon a ceramic slab for hole-reaming purposes;

40 FIG. 2 is a sectional view similar to FIG. 1 but showing the tool in the position it assumes at the end of a reaming operation; and

45 FIG. 3 is a reduced sectional view taken along the line 3—3 of FIG. 1.

50 Referring now to the drawings in detail, the stabilizing means of the present invention has, for exemplary purposes, been shown as being operatively applied to a reaming tool 10. The latter is of the type which is employed for the purpose of reaming out the cylindrical wall 12 of a hole 14 which has previously been drilled in a slab 16 of ceramic material, such as slate or marble, to the end that the wall surface of the hole is made frusto-conical as indicated at 18 in FIG. 2.

55 The reaming operation is carried out by way of a conventional drill press which serves to rotate the tool 10 and, at the same time, feed the tool toward the work, namely, the slab 16. Accordingly, the slab 16 is supported on a spacer sheet 20 which is preferably in the form of a sheet of plywood and, in turn, is supported upon the bed plate 60 or table 22 of the drill press. An oversize hole 24 is formed in the plywood sheet and the sheet is so positioned that this hole is in vertical register and axial alignment with the rotating chuck 26 of the drill press. The details of the drill press have not been shown and only the bed plate 22 and the chuck 26 have been illustrated herein. It will be understood that the drill press is of conventional design and includes manual means whereby the chuck 26, in connection with rotation thereof, may be moved vertically toward and away from the bed plate 65 22 in the usual manner of operation of a drill press. The slab 16 is supported upon the plywood sheet 20 with the previously drilled hole 14 in register with the hole 24 in

the sheet 20 and in axial alignment with the chuck 26 of the drill press.

The reaming tool 10 is of more or less conventional design, except for the provision therein of certain guideways by means of which the tool is caused to cooperate with the stabilizing means of the present invention. It is of the diamond abrasive type and comprises an inverted cup-shaped body 30. The latter embodies a circular top wall 31 from which there depends a side wall 32 having a cylindrical inside face 34 and an inverted frusto-conical outside face 36. The slant angle of the face 36 is commensurate with the slant angle of the wall surface 18 to be formed about the hole 14, such surface being indicated by dotted lines in FIG. 1. The slant height of the outside face 36 is somewhat in excess of the thickness of the slab 16 and also of the slant height of the finished wall surface 18.

Although it is contemplated that the abrasive surface of the tool 10 may be continuously frusto-conical, for a more effective abrasive action, the tool is provided with an annular series of elongated rectilinear abrasive segments 40. The latter are substantially square in transverse cross section. They are equally spaced on the outside face 36 of the side wall 32 of the tool body 30 and are soldered or otherwise mounted in grooves 42 (see FIG. 3) which are formed in said outside face 36. The upper ends of the segments 40 terminate flush with the flat upper circular face 44 of the top wall 31 of the tool body 30 and the lower ends of the segments terminate flush with the flat lower annular face 46 of the side wall 32 of the tool body. The segments 40 project outwardly beyond the frusto-conical outside face 36 so as to present flat working faces 47 which are spaced radially outwardly from said outside face 36. The tool 10 is provided with a vertical spindle 48 which projects upwardly from the central portion of the flat upper circular face 44, such shank being adapted for reception in the drill press chuck 26 as shown in FIG. 1.

For work upon marble, slate, granite and certain other ceramic materials, it is preferable that each abrasive segment 40 shall be in the form of a metallic matrix which is shaped as heretofore described and is impregnated with diamond particles. Although the actual reaming operation is conducted in the presence of a suitable coolant which is supplied to the work undergoing reaming and, to a certain extent, has a tendency to minimize friction during abrasion, it is a fact that the diamond particles project a slight distance outwardly of the matrices in which they are carried and establish an extremely high coefficient of friction between the rotating tool and the work with the result that the frictional drag upon the tool will set up vibrational effects which do not take place in connection with silicon and other types of abrasive materials.

The overall outside diameter of the extreme lower end of the side wall 32 of the tool body 30, including the segments 40, is approximately equal to or very slightly less than the diameter of the previously drilled hole 14 to the end that, as the chuck 26 and the spindle 48 and the chuck 26 are caused to descend or move downwards in the course of reaming operations, the lower end of the tool will properly enter the hole 14 and commence its reaming operation on the cylindrical wall 12 of the hole. The overall outside diameter of the extreme upper end of the side wall of the body of the tool 10, including the segments 40, is at least equal to and preferably is in excess of the diameter of the previously drilled hole 14 so that it is only necessary for the tool 10 to pass downwardly only part way of the slab 16 to effect the necessary reaming operation.

As previously stated, it has been found that a diamond abrasive reaming tool, such as has been heretofore described, when put to use in reaming a hole such as the hole 14, will frequently chatter due to the involved high frictional forces and the inability of the spindle 48 to maintain the tool accurately centered with respect to the

hole. The slightest deviation from axial coincidence with the hole will set up harmonic vibrations in the tool and the spindle and the resulting eccentricity will effect chipping or fracture of the relatively brittle ceramic material undergoing reaming. Such vibrations are especially noticeable when one or more of the abrasive segments 40 is minutely displaced out of its frusto-conical orbit, thereby setting both centrifugal and frictional forces into operation. To remedy this contingency, according to the present invention, stabilizing means 49 has been provided and this means is in the form of a rotatable stabilizing reaction hub 50 which is secured to the bed plate 22 in centered station with the hole 14 in the slab 16, i.e., in vertical register with the chuck 26 and the spindle 48, and in axial coincidence with the tool 10. As will be described presently, there is provided interengaging guide means between the tool 10 and the hub 50, this guide means being effective during the entire operative advancing stroke of the rotating reaming tool 10 to maintain the tool accurately centered with respect to the hole undergoing reaming.

Accordingly, the hub 50 is formed with a relatively deep socket 52 in the central portion of the underneath face 54 thereof, this socket fitting snugly over the outer race 56 of a ball bearing assembly 58. The inner race 60 of the assembly is securely fastened by means of a clamp screw 61 to the bed plate 22. When the bearing assembly 58 is secured in position on the bed plate 22 by way of the screw 61, the outer race 56 and the underneath face 54 of the reaction hub 50 are located a small distance above the horizontal upper surface 62 of the bed plate 22 by reason of the fact that the lower portion of the inner race 60 of the bearing assembly is provided with an annular depending spacing flange 63. Because of this spacing arrangement, the outer race 56 and the hub 50 are free to rotate about the vertical axis of the screw 61. The hub 50 is cylindrical and the diameter thereof is less than the internal diameter of the cylindrical inside wall face 34 of the tool body 30. The depth of the cup-shaped tool body 30 is greater than the height of either the screw 61 and the hub 50 in order that the tool may descend in telescopic fashion over these parts without interference during hole-reaming operations.

Two diametrically opposite eccentrically mounted cylindrical guide posts 64 project upwardly from the circular upper face 66 of the hub 50 and are adapted to project slidably through circular holes 68 in the top wall 31 of the tool body 30, the slidable fit being a snug one so that there will be no lateral play between the guide posts and the tool body. Each guide post 64 is provided with an integral depending reduced shank 70 which is threadedly received within a threaded bore 72 in the reaction hub 50. Vertically extending compression springs 74 surround the guide posts 64 and are adapted to have their upper ends bear or abut against the bottom surface of the top wall 31 of the tool body 30. The lower ends of the springs 74 rest upon the upper face 66 of the hub 50. The springs offer yielding reaction force to the manually initiated downward movement of the drill press chuck and the spindle 48 during hole-reaming operations and also serve to maintain the tool 10 elevated and out of contact with the work when the operating lever of the drill press is released by the operator. Screw driver slots 76 are formed in the upper ends of the guide posts 64 to facilitate installation of the posts on the reaction hub 50.

In the operation of the tool 10 and its stabilizing means 49, descent of the tool 10 upon the slab 16 will bring the extreme lower annular end of the tool into telescopic relationship with the cylindrical wall 12 of the hole 14 to be reamed so that the extreme lower end regions of the working faces 47 of the various reaming segments 40 will make contact with the upper rim 78 of the wall 12 and thus commence the reaming operation. Continued descent of the tool 10 will progressively effect reaming of the wall 12 and such descent of the tool will be continued until such time as the lower annular rim of the tool has

passed completely through the slab 16 and the mean diameter of the reamed wall 18 has assumed the desired or predetermined dimension as shown in FIG. 2. It will be understood, of course, that prior to performance of the downward operative abrasive stroke of the reaming tool 10, the operator will, before effecting rotation of the drill press spindle, lower the chuck, the spindle and the tool bodily as a unit and cause the upper ends of the guide posts 64 to enter the holes 68. After such entry of the guide posts into the holes, the drill press may be started to rotate the chuck 26 and commence resultant rotation of the tool 10, after which a drive will be established for the reaction hub 50 which will rotate in unison with the tool during the actual reaming operation. After the reaming operation is complete, the operator will release the operating handle of the drill press and the chuck 26 and the tool 10 will automatically be restored to their initial elevated positions under the influence of the compression springs 74.

If the slab 16 undergoing treatment is relatively massive, as if, for example, the one inch thick marble or slate slab of a regulation sized pocket billiard table, it may be necessary to remove the stabilizing assembly 49 after each hole has been reamed so that the slab may be repositioned on the bed plate 22 for reaming of the next hole. Accordingly, the screw 61 which constitutes the sole means for securing the assembly 49 in its operative position may be provided with an Allen type socket 80 to facilitate its removal by use of an Allen wrench. Thus, for each hole which is reamed, the assembly 49 will be removed and replaced. On the other hand, if the slab is relatively light and easily portable, the assembly 49 may be left permanently in position on the bed plate 22 and the slab 16 lifted over the assembly for shifting or removal purposes, the stroke of the drill press chuck being such as to afford the necessary clearance between the tool 10 and the assembly 49 for such shifting or removal of the slab.

The invention is not to be limited to the exact arrangement of parts shown in the accompanying drawings or described in this specification as various changes in the details of construction may be resorted to without departing from the spirit or scope of the invention. For example, while the reaming tool which is illustrated and described has been designed specifically for imparting a frusto-conical configuration to the inside wall surfaces of previously drilled holes in marble, slate, granite and similar ceramic materials, it is obvious that, by suitable modification of the shape of the abrasive surfaces of such tool, other configurations may be imparted to the wall surfaces of cylindrical holes or other openings in such materials. Therefore, only insofar as the invention has particularly been pointed out in the accompanying claims is the same to be limited.

Having thus described the invention what I claim as new and desire to secure by Letters Patent is:

1. An apparatus adapted to ream the inside wall surface of a preformed hole in a ceramic slab and comprising a bed plate for supporting the slab in a horizontal position, a reaming tool mounted for rotation about a vertical axis and vertically movable bodily toward and away from said bed plate, a peripheral abrasive surface formed on said tool and adapted to enter the hole for wall-reaming purposes during vertical descent of the tool

toward the bed plate, a stabilizing reaction hub mounted for rotation on said bed plate about an axis coincident with the vertical axis of rotation of the reaming tool, and a plurality of circumferentially spaced guide posts 5 projecting upwardly from said hub at eccentric regions thereon, said tool being provided with a plurality of guideways within which said guide posts are axially slidable during descent of the tool toward the bed plate.

2. An apparatus as set forth in claim 1 and wherein the 10 guide posts are cylindrical and the guideways are in the form of cylindrical bores within which the guide posts are slidable with a snug fit.

3. An apparatus as set forth in claim 2 and including, 15 additionally, compression springs surrounding the guide posts and having their upper ends bearing against the reaming tool and their lower ends bearing against the reaction hub.

4. An apparatus as set forth in claim 2 and wherein the 20 guide posts are two in number and are disposed diametrically opposite one another on the reaction hub, and the cylindrical bores within which said guide posts are received are disposed in the peripheral regions of the reaming tool.

5. An apparatus adapted to ream the inside wall surface of a hole in a ceramic slab and comprising a bed 25 plate for supporting the slab in a horizontal position, a reaming tool mounted for rotation about a vertical axis and vertically movable bodily toward and away from said bed plate, a peripheral abrasive surface formed on 30 said tool and adapted to enter the hole for wall-reaming purposes during vertical descent of the tool toward the bed plate, stabilizing means for said tool mounted on the bed plate and engageable with the tool for preventing eccentric wobbling of the latter, said stabilizing means comprising a ball bearing assembly including inner and outer races, a fastening screw removably securing said inner race to the bed plate in axial coincidence with the reaming tool, a reaction hub telescopically received over said outer race and rotatable bodily therewith, and a plurality of 35 circumferentially spaced guide posts projecting upwardly from said hub at eccentric regions thereon, said tool being provided with a plurality of guideways within which said guide posts are axially slidable during descent of the tool toward the bed plate.

6. An apparatus as set forth in claim 5 and wherein the 40 guide posts are cylindrical and the guideways are in the form of cylindrical bores within which the guide posts are slidable with a snug fit.

7. An apparatus as set forth in claim 6 and wherein the 45 guide posts are two in number and are disposed diametrically opposite to one another on the hub, and the cylindrical bores within which said guide posts are received are disposed in the peripheral regions of the reaming tool.

8. An apparatus as set forth in claim 7 and including, 50 additionally, compression springs surrounding said guide posts and having their upper ends bearing against the reaming tool and at their lower ends bearing against the hub.
